(57) **CLAIM**

The ornamental design for an aircraft weapon system, as shown and described.

DESCRIPTION

FIG. 1 is a perspective view of an aircraft weapon system; FIG. 2 is a top plan view of the aircraft weapon system of FIG. 1;

FIG. 3 is a bottom plan view of the aircraft weapon system of FIG. 1;

FIG. 4 is a right side elevation view of the aircraft weapon system of FIG. 1;

FIG. 5 is a left side elevation view of the aircraft weapon system of FIG. 1;

FIG. 6 is a front elevation view of the aircraft weapon system of FIG. 1; and,

FIG. 7 is a rear elevation view of the aircraft weapon system of FIG. 1.

The broken lines in the drawings represent unclaimed environmental subject matter and form no part of the claim.
